UNITED STATES PATENT OFFICE.

LEWIS B. HAINES AND MARY E. HAINES, OF TAR RIVER, OKLAHOMA.

QUILTING-FRAME.

1,300,724.

Specification of Letters Patent. Patented Apr. 15, 1919.

Application filed September 13, 1918. Serial No. 254,025.

To all whom it may concern:

Be it known that we, LEWIS B. HAINES and MARY E. HAINES, citizens of the United States, residing at Tar River, in the county 5 of Ottawa and State of Oklahoma, have invented certain new and useful Improvements in Quilting-Frames, of which the following is a specification.

This invention relates to quilting frames 10 of the collapsible or knockdown type.

The main object of the invention is to provide a simply constructed frame of this character, the parts of which may be quickly and easily knocked down or set up and when 15 collapsed will come within the regulations for parcel post shipping.

Another object is to provide improved means for locking the material carrying bars in adjusted position.

20 Another object is to provide yieldable means for holding the supporting legs in operative position and permit them to be quickly separated for collapsing the frame.

With the foregoing and other objects in 25 view, which will appear as the description proceeds, the invention resides in the combination and arrangement of parts and in the details of construction hereinafter described and claimed, it being understood that 30 changes in the precise embodiment of the invention herein disclosed may be made within the scope of what is claimed without departing from the spirit of the invention.

In the accompanying drawings:—

35 Figure 1 represents a side elevation of a quilting frame constructed in accordance with this invention.

Fig. 2 is a plan view with parts broken out and in section.

40 Fig. 3 is a transverse section taken on the line 3—3 of Fig. 1 with the frame shown in open operative position.

Fig. 4 is a detail sectional view through 45 one end of one of the material carrying side bars, and

Fig. 5 is a detail sectional view through one of the upper ends of a supporting leg showing the connection between the side bar and said leg.

50 In the embodiment illustrated, the frame constituting this invention comprises two side bars, 1 and 2, which are here shown composed of wood, but obviously they may be constructed of any suitable material, and 55 made either solid or hollow. These bars are each constructed of detachably connect-

ed sections, two sections 3 and 4 being here shown, although there may be more if found desirable. In the meeting ends of these sections, one has a socket 5 and the other a reduced extension or nipple to fit in said socket, the coöperating faces of which are preferably threaded to hold the sections against accidental separation. A plurality of material attaching devices are indicated 60 at 7, and may be of any desired construction, capable of securing the material to be operated on to the side bars.

These side bars are supported at their opposite ends by two pairs of legs 8 and 9 which cross each other midway their length as shown at 10 with their meeting faces chamfered or mortised for interlocking engagement, the shape of the mortise varying according to the distance apart it is desired 75 the upper ends of the legs shall be positioned. These legs at their points of intersection are pivotally connected by bolts 11 which project beyond the inner faces of the inner bars and each has a stop 13 80 at its outer or free end between which and the leg 9 is arranged a coiled spring 12 which exerts its tension to normally hold the legs in interlocked engagement.

The upper ends of the legs 8 and 9 are 85 apertured to receive the ends of the side bars 1 and 2 and to form bearings therefor. These ends are reduced as shown at 15 with shoulders 14 at their inner ends forming abutments for limiting the insertion of the 90 pintle ends 15 in the bearings of said legs. When constructed of wood as shown in the drawings, these pintles are longitudinally grooved and are provided with wear sleeves 16 having similar grooves 17 to fit within 95 the grooves of the pintles and hold the sleeves against turning thereon. These interfitting grooves also operate to form a ratchet which coöperates with a pawl 18 carried by the end of the leg in which the 100 pintle is inserted as is shown clearly in Fig. 5. This pawl 18 has a flattened head 19 at its outer end to facilitate its actuation and is provided with a stop in the form of a washer 20 disposed adjacent said head and 105 against which bears one end of a coiled spring 21, the other end bearing against a plate 22 on the leg in connection with which it is used. This plate 22 forms a closure for the bore in which the pawl is mounted as is 110 shown clearly in Fig. 5. This pawl 18 has a beveled nose 23 which projects into the

bearing in which the pintle 15 is mounted so as to engage the groove therein and yieldably lock the pintle in connection with the leg. This pawl 18 is also rotatable in the bore in which it is mounted so that either the straight face or the beveled face of its nose may be positioned in one direction or the other to provide for the locking of the pintle or to permit it to be rotated in either direction at the will of the operator.

Four of these pawls are provided as is shown clearly in Fig. 2 for securing the opposite ends of the side bars 1 and 2 to their supporting legs 8 and 9.

In the use of this improved quilting frame, the sections 3 and 4 of the side bars are connected as shown in Figs. 1 and 2. The legs then have their mortised faces engaged as shown in Fig. 3, and they are then ready to receive the pintle ends 15 of the side bars, which are inserted in the bearings at the upper ends of said legs, and are secured therein by engagement of the pawls 18 with the grooves 17 in said pintles.

The quilt, comfort or other article to be operated on is then attached at its opposite ends or sides to the bars 1 and 2 by means of the fastening elements 7 and the major portion of the quilt is wound up on one of the bars so that as the material is quilted it may be fed or rolled from one bar to the other, being unwound from one and wound up on the other. After the proper exposure of material has been made, the bars are locked against further turning by changing the position of the pawls 18 so that their straight faces will engage the side walls of the grooves in the pintles to lock them against turning.

When it is desired to collapse the frame for shipping, storage or other purposes, the side bars are first removed from their bearings in the legs by disengaging the pawls 18 and slipping them out of the bearings, and these bars are then separated into sections by unscrewing the members 5 and 6 therefrom. The legs 8 and 9 may be folded by springing the outer leg 8 outward against the tension of its spring 12 a sufficient distance to disengage its mortised face from that of leg 9. These legs may then be folded flat one on the other to occupy a minimum amount of space, and in connection

with the sectional side bars may be packaged for storage or shipment.

The legs may be folded without disengaging the side bars when it is found desirable to do so to reduce the space which the frame occupies temporarily so that it may be quickly returned to operative position by simply grasping the side bars and forcing them outwardly in opposite directions.

The foregoing description and the drawings have reference to what may be considered the preferred or approved form of our invention. It is to be understood that we may make such changes in construction and arrangement and combination of parts, materials, dimensions, etc., as may prove expedient and fall within the scope of the claimed invention.

Having thus fully described our invention, what we claim as new and desire to secure by Letters Patent, is:—

1. A frame of the class described comprising material supporting bars, pivotally connected legs having bearings to receive said bars, yieldable means for holding the legs in adjusted position, and means for detachably locking the bars in adjusted position relatively to the legs.

2. A quilting frame comprising side bars having material attaching elements, pairs of crossed legs for supporting the ends of the bars, said legs being mortised on their meeting faces at their points of intersection for interlocking engagement, pivot bolts extending through said mortised portions of the legs to pivotally connect them and having coiled springs mounted thereon whereby the legs are yieldably held in interlocked position.

3. A frame of the class described comprising sectional side bars detachably connected, foldable legs for supporting said side bars, means for yieldably locking said legs in operative open position, and means for locking the side bars in adjusted position on said supports.

In testimony whereof we affix our signatures in presence of two witnesses.

LEWIS B. HAINES.
MARY E. HAINES.
